UNITED STATES PATENT OFFICE.

LEONARD A. YOUNG, OF DETROIT, MICHIGAN.

DESIGN FOR A LATCH-CASING.

46,305.

Specification for Design.

Patented Aug. 18, 1914.

Application filed June 12, 1914. Serial No. 844,829. Term of patent 14 years.

To all whom it may concern:

Be it known that I, LEONARD A. YOUNG, a citizen of the United States of America, residing at Detroit, in the county of Wayne and State of Michigan, have invented a new, original, and ornamental Design for a Latch-Casing, of which the following is a specification, reference being had therein to the accompanying drawing, forming part thereof, in which—

Figure 1 is a front elevation of the casing showing my new design, and Fig. 2 is a side elevation thereof.

I claim:—

The ornamental design for a latch casing, as shown.

LEONARD A. YOUNG.
